(57) **CLAIM**

The ornamental design for a vehicle headlamp, as shown and described.

DESCRIPTION

FIG. 1 is a top perspective view of a vehicle headlamp; a mirror image vehicle headlamp is evident from the vehicle headlamp shown;

FIG. 2 is a front view thereof;

FIG. 3 is a back view thereof;

FIG. 4 is a top view thereof;

FIG. 5 is a bottom view thereof; and,

FIG. 6 is a right-side view thereof.

The dashed broken lines depict portions of the vehicle headlamp that form no part of the claimed design.
